PORTABLE RACK

Warren T. George, 1611 Clark Ave., Billings, Mont.
Filed June 19, 1961, Ser. No. 117,865
10 Claims. (Cl. 294—5.5)

This invention relates to new and useful improvements in clothes handling apparatus for use particularly, although not necessarily in laundries, dry cleaning, clothing and other establishments, and has for its primary object to provide, in a manner as hereinafter set forth, novel means whereby a large number of hanger-mounted garments may be expeditiously and safely carried from place to place with a minimum of effort.

Another very important object of the present invention is to provide an apparatus of the aforementioned character comprising a readily detachable handle of a unique construction whereby a loaded rack may be easily transported with one hand.

Still another important object of the invention is to provide an improved garment handling apparatus of the character set forth which embodies unique means for connecting the loaded hangers comprising a single order and for removing a plurality of such loaded hangers from the portable rack with one hand as for delivery to a customer.

Another important object of the invention is to provide a portable clothes rack wherein the operator is not required to touch the usual hanger hooks with the hands, thus substantially eliminating the danger of injury from this source.

Other objects of the invention are to provide a portable clothes rack of the character set forth which will be comparatively simple in construction, strong, durable, compact, of light weight and which may be manufactured at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

FIGURE 1 is a view in side elevation, showing a loaded portable clothes rack embodying the present invention hung on a permanent rack;

FIGURE 2 is a cross-sectional view, taken substantially on the line 2—2 of FIGURE 1;

FIGURE 3 is a perspective view, showing an empty portable rack mounted on a removable handle;

FIGURE 4 is a vertical sectional view on an enlarged scale, taken substantially on the line 4—4 of FIGURE 3;

FIGURE 5 is a plan view of the hanger connector and lifter; and

FIGURE 6 is a perspective view of a modified form of portable rack.

Referring now to the drawing in detail and to FIGURES 1 and 2 thereof in particular, it will be seen that reference numeral 7 designates generally a portable clothes rack embodying the present invention. The rack 7 which may be of any suitable dimensions and material, comprises a horizontal rod or shaft 8 having fixed thereon adjacent the ends thereof a pair of upstanding suspension hooks 9. The hooks 9 are engageable with a conventional stationary rack 10 mounted in a business establishment or a delivery vehicle for removably hanging the rack 7 thereon. Fixed vertically on the ends of the rod or shaft 8 is a pair of substantially rectangular, depending plates 11.

To handle the rack 7 with a plurality of loaded hangers on the rod 8 thereof, as indicated at 12, a handle 13 is provided. The carrying handle 13 includes an angulated rod or bar 14 having on one end thereof a yoke 15

2

in which a hand-grip 16 is mounted. Fixed on the other or lower end of the bar 14 is a generally U-shaped saddle 17 which is adapted to straddle the back of the wrist or forearm of the user, as indicated at 18. Thus, the lower portion of the bar 14 and the saddle 17 constitute an arm brace for the handle 13. Fixed to the angulated bar 14 at an intermediate point is a generally U-shaped member or clip 19. The clip 19 is for the reception of either of the plates 11 for removably mounting the carrying handle 13 on either end of the rod 8. In the embodiment shown, one end portion of the clip 19 is provided with an open slot 20 which accommodates the rod 8.

For connecting a plurality of the hangers 12 and permitting them to be handled simultaneously with one hand, a lifting handle 21 is provided. The handle 21 includes a pair of elongated, parallel rings or loops 22 which are integrally connected in the embodiment shown.

It is thought that the use of the invention will be readily understood from a consideration of the foregoing.

Briefly, the portable rack 7 is hung on the stationary rack 10 and the hangers 12 are loaded on the rod 8. As shown in FIGURE 1 of the drawing, several of the hangers 12 comprising a single order are connected by one of the lifting handles 21 prior to mounting said hangers on the rack 7. This is readily accomplished by simply inserting the suspension hooks of the hangers 12 through one of the rings or loops 22. When the loaded rack 7 is to be carried or transported, the clip 19 is engaged with one of the plates 11 for mounting the handle 13 on either end of the rod 8. The hand of the operator is inserted through the yoke 15 for gripping the grip 16. Then, with the saddle 17 bearing against the back of the wrist or forearm of the user, the loaded rack 7 may be removed from the stationary rack 10 and carried to the desired location, such as a delivery truck also equipped with a stationary rack, in an obvious manner. The slot 20 in the clip 19, receiving the rod 8, positively prevents relative lateral movement between the handle 13 and the rack 7. When delivering a plurality of the loaded hangers 12 to a customer said hangers may be lifted simultaneously from the rod 8 through the medium of the handle 21. When doing this the fingers of the deliveryman may be inserted through the lower ring or loop 22 through which the hanger hooks pass. This permits the unobstructed other or upper loop or ring 22 to be presented to the customer. Thus, the operation may be completed without either party touching the hanger hooks. If desired, the handles 21 may also be utilized for grouping the loaded hangers and mounting same on the rack 7.

In the embodiment of FIGURE 6 of the drawing, there is shown a portable clothes rack 23 in the form of a wire garment hanger comprising a generally rectangular frame 24 provided with a suspension hook 25. The frame 24 includes a horizontal rod 26 for receiving thereon the loaded hangers 12 in the manner of the rod 8. The frame 24 further includes end portions 27 having fixed vertically thereon plates 28 which are substantially similar to the plates 11. The plates 28 are selectively engageable in the U-shaped member or clip 19 for mounting the handle 13 on either end of the rack 23.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A portable clothes rack for mounting on a support and comprising a horizontal rod for receiving thereon a plurality of loaded garment hangers, a carrying handle

for the rod, said handle including an angulated bar, a hand-grip on one end of the bar, an arm saddle on the other end of the bar, and a generally U-shaped clip on an intermediate portion of the bar, said rack further comprising a plate on at least one end portion of the rod removably inserted in the clip for detachably securing the handle on the rod.

2. A portable clothes rack for mounting on a support and comprising a horizontal rod for receiving thereon a plurality of loaded garment hangers, a carrying handle for the rod, said handle including an angulated bar, a hand-grip on one end of the bar, an arm saddle on the other end of the bar, and a generally U-shaped clip on an intermediate portion of the bar, said rack further comprising plates on the end portions of the rod selectively inserted in the clip for detachably securing the handle on either end portion of the rod, said clip having an open slot in one end portion thereof receiving the rod and securing the handle against lateral movement relative thereto.

3. A clothes handling apparatus comprising a portable rack for mounting on a support and including a horizontal rod for receiving thereon a plurality of loaded garment hangers, vertical plates on the ends of said rod, and a carrying handle for the rod, said handle comprising a hand-grip, a generally U-shaped clip on said hand-grip selectively receiving the plates and mounting the handle on either end of the rod, and an arm brace connected to the clip, said arm brace including a bar and an arm-receiving saddle on an end of said bar.

4. A clothes handling apparatus comprising a portable rack for mounting on a support and including a horizontal rod for receiving thereon a plurality of loaded garment hangers, vertical plates on the ends of said rod, and a carrying handle for the rod, said handle comprising a hand-grip, a generally U-shaped clip on said hand-grip selectively receiving the plates and mounting the handle on either end of the rod, and an arm brace connected to the clip, said arm brace including a bar and an arm-receiving saddle on an end of said bar, said clip having a slot in one end portion receiving the rod.

5. A portable clothes rack comprising a wire garment hanger including a generally rectangular frame for mounting on a support, said frame including vertical end portions and a horizontal rod for receiving thereon a plurality of loaded garment hangers, a carrying handle, and means removably securing said handle on either of said end portions of the frame, said carrying handle including a hand-grip and a generally U-shaped clip mounted thereon, and vertical plates on said end portions of the frame selectively and removably inserted in the clip, said handle further including an arm brace affixed to the clip and comprising a saddle for straddling an arm.

6. A portable clothes handling device comprising an

elongated horizontal garment hanger receiving rod, a mounting member rigid with one end of the rod, and a carrying handle, said handle including an elongated rigid bar, a hand-grip on one end of the bar, an arm saddle on the other end of the bar, and mounting means fixed to the bar at an intermediate point therealong, said mounting means releasably engaging the mounting member for enabling a lifting of the rod through the handle.

7. A clothes rod carrying handle comprising a hand-grip, an arcuate arm saddle located below the hand-grip in substantial vertical alignment therewith, a bar rigidly interconnecting the hand-grip and arm saddle, an intermediate portion of said bar projecting forwardly of said hand-grip and arm saddle between said hand-grip and said arm saddle, and a vertically extending clip fixed to the intermediate portion of the bar and located forward of the hand-grip and arm saddle, said clip consisting of two spaced parallel vertical legs interconnected at their lower ends.

20 8. The handle of claim 7 wherein one of said vertical legs includes a centrally located vertical slot extending downwardly from the upper end thereof.

9. A portable clothes handling device comprising an elongated horizontal garment hanger receiving rod, mounting means rigid with one end of the rod, and a carrying handle, said handle including an elongated rigid bar, an arm saddle on one end of said bar, a hand-grip on said bar in general alignment with and spaced longitudinally from said arm saddle, and mounting member fixed to the bar and projecting therefrom, said mounting member releasably engaging the mounting means for enabling a lifting of the rod through the handle.

10. A portable clothes handling device comprising an elongated horizontal garment hanger receiving rod, an enlarged mounting member rigid with one end of the rod, and a carrying handle, said handle including an elongated rigid bar, an arm conforming saddle on one end of said bar, a hand-grip on said bar in general alignment with and spaced longitudinally from said arm conforming saddle, and mounting means fixed to the bar, said mounting means releasably engaging the mounting member for enabling a lifting of the rod through the handle.
